POPGUN

Charles F. Lefever, Plymouth, Mich., assignor to
Daisy Manufacturing Company, Plymouth,
Mich., a corporation of Michigan

Application April 24, 1943, Serial No. 484,411

6 Claims. (Cl. 46—194)

The invention relates to pop guns and has for its primary object the obtaining of a construction which can be manufactured at low cost and from materials which are available for this purpose during the present national emergency. To this end the invention consists in the construction as hereinafter set forth.

In the drawings:

Fig. 1 is a perspective view of my improved pop gun;

Fig. 2 is a longitudinal section through the barrel of the gun;

Fig. 3 is a section on line 3—3, Fig. 2;

Fig. 4 is a cross section on line 4—4, Fig. 2;

Fig. 5 is a section on line 5—5, Fig. 2;

Fig. 6 is a sectional elevation showing a modified construction; and

Fig. 7 is a cross section on line 7—7, Fig. 6.

My improved pop gun is of that type in which the noise is produced by the rupture of a paper strip subjected to air pressure. Heretofore guns of this type have been provided with various means for clamping the paper in sealing contact with the air chamber. In the present construction I accomplish this by novel and simple means dispensing with parts heretofore necessary. Also, the construction is one which may be made almost entirely from wood and from scrap stock which has little value for other purposes.

As illustrated, my improved pop gun is in the form of a pistol having a barrel A and handle B both preferably formed of wood. The barrel A is bored and counterbored from opposite ends to form therewithin an annular shoulder C located a short distance in rear of the forward end. It is also cut away on opposite sides to form a slot D extending transversely therethrough adjacent to the shoulder C for the passage of a paper strip E. Within the rear portion of the barrel is a sleeve member F which has a bore F' in its forward portion constituting an air chamber and a bore F² of slightly smaller diameter in its rear portion with a shoulder F³ therebetween. The forward end of the sleeve is slightly tapered to form a narrow annular face F⁴ adapted in the forward movement of the sleeve to press the paper strip against the shoulder C. The latter is provided with a gasket or facing C' formed of a leather, rubber or other yielding material so that the paper will be pressed against the face F⁴ to seal the front end of the air chamber. G is a piston within the bore F' preferably formed of a cup of leather or other suitable material. This piston is secured to the forward end of the shank or rod H in the bore F² extending out from the

rear end thereof with a knob H' at its rear end. The piston is secured by a screw G' with metal washers G² and G³ within and in rear of the cup. The latter is adapted to engage the shoulder F³ to limit the rearward movement of the piston. The sleeve F is longitudinally movable within the barrel A which movement is limited by a pin or dowel I extending inward from one side of the barrel to engage a slot I' in the sleeve. The amount of movement permitted is sufficient for the sleeve to clear the slot D in its rearmost position and to press against the gasket C' in its forward position. At one side of the barrel just in rear of the slot D is a magazine J for holding a roll of paper strip. This magazine has a slot J' in its forward side through which the paper is drawn and then passed through the slot D. The handle B is mortised into the lower face of the barrel as indicated at B' and secured by glue. It is also provided with an aperture B³ in the forward portion thereof to simulate a trigger guard. With the construction as described, the friction between the cupped piston G and the sleeve F is sufficient to move the latter with the former as far as permitted by the slot I'. Thus, assuming that the rod H has been drawn rearward and the piston G is in the position shown in Fig. 2, the sleeve F will be in rear of the slot D so as to permit the paper strip E to be drawn through said slot from the magazine J. To fire the gun the handle B is grasped by the right-hand of the operator who also inserts a finger through the aperture B³ as if he were pulling upon a trigger. The knob H' is then moved forward by the left-hand and on account of the friction between the piston and sleeve will advance the latter to clamp the paper strip E against the gasket C'. The continued forward movement of the knob H' and rod H will move the piston G within the bore F' compressing the air therein until sufficient pressure is attained to rupture the paper. This will cause a loud report.

In Figs. 6 and 7 a slightly modified construction is shown where the handle has a portion B⁴ attached to the barrel and another portion B⁵ extending through a slot in the barrel and attached to the sleeve F. The latter portion has a mortised slot B⁶ engaged by a tongue B⁷ on the portion B⁴. A pin B⁸ extending through both members and engaging a slot B⁹ in the tongue B⁷ limits the amount of movement permitted. With this construction the forward movement of the sleeve F to clamp the paper strip is effected by the grasp of the handle and the rod H is only used for operating the piston to compress the air. However,

when the rod is drawn rearward, the washer G³ engaging the shoulder F³ will move the sleeve F rearward so as to clear the slot D.

As above stated, the construction is one in which the parts can be made from scrap stock so that the cost of material is negligible. Also the time and labor required for fashioning and assembling the parts is relatively small.

What I claim as my invention is:

1. A pop gun comprising a barrel transversely slotted for the passage of a paper strip therethrough, an annular seat or shoulder within said barrel forward of said slot, a sleeve movable within the rear portion of said barrel constituting an air chamber and adapted when moved forward to press said paper strip against said seat sealing the forward end of said air chamber, a piston within said air chamber and a piston rod for actuating the same extending out from the rear end of said sleeve and barrel, adapted when moved forward to compress the air within said chamber and rupture the strip.

2. A pop gun comprising a barrel transversely slotted for the passage of a paper strip therethrough, an annular seat or shoulder within said barrel forward of said slot, a sleeve movable within the rear portion of said barrel into and out of contact with said paper strip and seat, the forward portion of said sleeve constituting an air chamber, a piston in said air chamber, an actuating rod for said piston extending rearward beyond said sleeve and barrel, a knob at the rear end of said rod, and means operating in advance of the forward movement of said piston under actuation of said knob and rod for pressing said sleeve against said paper strip and seat to seal the forward end of said air chamber, whereby the forward movement of said piston in said chamber will compress the air therein and rupture said paper strip.

3. A pop gun comprising a barrel transversely slotted for the passage of a paper strip therethrough, an annular seat or shoulder within said barrel forward of said slot, a sleeve movable within the rear portion of said barrel into and out of contact with said paper strip and seat, the forward portion of said sleeve constituting an air chamber, a piston in said air chamber, an actuating rod for said piston extending rearward beyond said sleeve and barrel, a knob at the rear end of said rod, means operating in advance of the forward movement of said piston under actuation of said knob and rod for pressing said sleeve against said paper strip and seat to seal the forward end of said air chamber, whereby the forward movement of said piston in said chamber will compress the air therein and rupture said paper strip, and a magazine attached to

said barrel on one side thereof for holding a roll of said paper strip.

4. A pop gun comprising a barrel transversely slotted for the passage of a paper strip therethrough, an annular seat or shoulder within said barrel forward of said slot, a sleeve movable within the rear portion of said barrel into and out of contact with said paper strip and seat, the forward portion of said sleeve constituting an air chamber, a piston in said air chamber, an actuating rod for said piston extending rearward beyond said sleeve and barrel, a knob at the rear end of said rod, means operating in advance of the forward movement of said piston under actuation of said knob and rod for pressing said sleeve against said paper strip and seat to seal the forward end of said air chamber, whereby the forward movement of said piston in said chamber will compress the air therein and rupture said paper strip, and a magazine attached to said barrel on one side thereof for holding a roll of said paper strip, said magazine having a cylindrical recess open at the top for the insertion of said roll and a slot in its side through which the strip is drawn into the slot through said barrel.

5. A pop gun comprising a barrel forming an air chamber and transversely slotted for the passage of a paper strip therethrough, an annular seat or shoulder within said barrel forward of said slot, a sleeve movable within the rear portion of said barrel, means for limiting the movement of said sleeve within said barrel, a piston within said air chamber frictionally engaging said sleeve, and a rod extending rearward from said piston beyond the rear end of said sleeve and barrel, whereby the forward movement of said rod will first move said sleeve into sealing contact with said strip and will then compress the air in said chamber to rupture the strip.

6. A pop gun comprising a barrel transversely slotted for the passage of a paper strip therethrough, an annular seat or shoulder within said barrel forward of said slot, a sleeve within the rear portion of said barrel movable therein into and out of contact with said paper strip and seat, said sleeve constituting an air chamber, a handle having a portion secured to said barrel and another portion secured to said sleeve whereby the relative movement of said portions when grasped by the hand of the operator will press said sleeve into sealing contact with said strip and seat, a piston within said air chamber, and a piston rod extending rearward from said piston and beyond the rear end of said sleeve and barrel whereby the forward movement of said piston will compress the air within said chamber and rupture said strip.

CHARLES F. LEFEVER.
